US00D978100S

(12) **United States Design Patent** (10) **Patent No.:** **US D978,100 S**
(45) **Date of Patent:** **** Feb. 14, 2023**

(54) **RADIO COMMUNICATION DEVICE**

(71) Applicant: **ICOM INCORPORATED**, Osaka (JP)

(72) Inventor: **Haruki Nishizawa**, Osaka (JP)

(73) Assignee: **ICOM INCORPORATED**, Osaka (JP)

(**) Term: **15 Years**

(21) Appl. No.: **29/773,174**

(22) Filed: **Mar. 8, 2021**

(30) **Foreign Application Priority Data**

Sep. 9, 2020 (JP) ..... 2020-019280 D

(51) **LOC (14) Cl.** **14-03**

(52) **U.S. Cl.**

USPC **D14/137; D14/157; D14/188**

(58) **Field of Classification Search**

USPC D14/137, 157, 188; D16/200-255;
D18/11, 36-43, 99

CPC H04B 1/082; H04B 1/086; B60R 11/02;
B60R 11/0258

(57) **CLAIM**

The ornamental design for a radio communication device, as shown and described.

DESCRIPTION

FIG. 1 is a first perspective view of a radio communication device showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
